THOMAS L. MURPHY, OF EASTON, PENNSYLVANIA, ASSIGNOR TO INGERSOLL-RAND COMPANY, OF JERSEY CITY, NEW JERSEY, A CORPORATION OF NEW JERSEY

VALVE MECHANISM FOR ROCK DRILLS

Application filed September 21, 1928. Serial No. 307,486.

This invention relates to rock drills, but more particularly to a valve mechanism intended for effecting the distribution of pressure fluid to the ends of the cylinder.

5 One object of the invention is to prevent a fluttering action of the valve due to the suction created by the pressure fluid flowing over the raised end of the valve to the ends of the cylinder.

10 Other objects will be in part obvious and in part pointed out hereinafter.

In the drawings in which is shown a preferred modification of the invention and in which similar reference characters refer to 15 similar parts,

Figure 1 is a longitudinal sectional elevation of the rock drill having the invention applied thereto,

Figure 2 is a plan view of the distributing 20 valve, and

Figure 3 is a longitudinal side elevation of a plunger used for maintaining the valve firmly seated in its limiting positions.

Referring to the drawings, A designates 25 generally a rock drill having a cylinder B in which is disposed a reciprocating hammer piston C. The cylinder B in this instance is provided with a pair of exhaust ports D and E which are controlled by the piston C. The 30 piston illustrated is provided with a forward extension F which extends slidably through a front cylinder washer G disposed in the front end of the cylinder to form a closure for a piston chamber H wherein the piston C reciprocates. A closure is provided in this 35 instance for the rearward end of the cylinder in the form of a back cylinder washer J, said back cylinder washer J being seated in an enlarged bore K in the rearward end of the cylinder B.

In the rearward end of the bore K is disposed rotation mechanism comprising a rifle bar L which extends through the back cylinder washer J and interlocks slidably with the 45 piston C in a well known manner. The rifle bar L has the usual head O in which are disposed spring pressed plungers P which operate with teeth Q of a rotation ratchet R for imparting a rotary movement to the piston and thus also to a working implement 50

against which the piston is adapted to strike. The rotation ratchet R encircles the head O of the rifle bar and in this instance acts as a seat for a back head S disposed within the rearward end of the cylinder B to which it 55 may be secured in any suitable and well known manner.

The back head S is provided with a chamber T in which is disposed a throttle valve U having a central chamber V into which pressure fluid from a suitable source of supply may be constantly admitted. The throttle valve U is of the rotary type and accordingly has a lever W whereby said throttle valve may be manipulated. In the wall of the 60 chamber T is a port X which, when the throttle valve is in the open position, registers with a passage Y leading from the valve chamber T to a supply reservoir Z in the front end of the back head S.

Interposed between the back cylinder washer J and the rotation ratchet R is a valve mechanism whereby the distribution of pressure fluid to the ends of the cylinder is effected. The valve mechanism comprises a 65 valve chest b having a valve chamber c in its front end and for one side of which the back cylinder washer J forms a closure. The valve chamber c is in constant communication with the supply reservoir Z through a supply passage d in the rotation ratchet R and the valve chest b.

The distribution of pressure fluid from the valve chamber to the ends of the cylinder is effected by an oscillatory plate distributing valve e which encircles the rifle bar L and is provided on its transverse median line with a fulcrum f whereon said valve is adapted to rock. The admission of pressure fluid to the rearward end of the cylinder is effected 80 through a rearward inlet passage g in the back cylinder washer J, and the admission of pressure fluid to the front end of the piston chamber H is effected through a front inlet passage h leading through the back cylinder washer J and through the cylinder B to the front end of the piston chamber.

The parts thus far described are well known in the art to which the present invention pertains and are merely referred to 100

briefly in order to insure a better understanding of the advantages of the invention and the manner in which it cooperates with the valve *e* towards obtaining the objects sought.

In accordance with the practice of the invention, the valve chest *b* is provided with a pair of plunger chambers *j* and *k* which are disposed perpendicularly with respect to the 10 valve chamber *c* and have bores *o* at their front end which opens into the valve chamber *c*. Within the plunger chambers *j* and *k* are disposed plungers *p* and *q* respectively and said plungers have projections *r* at their 15 forward ends which extend slidably through the bores *o* to enable said plungers to bear against the wing portions of the valve *e*.

The plunger chambers *j* and *k* are provided at their rearward ends with exhaust passages 20 *s* of small cross sectional area for the escape of pressure fluid utilized for actuating the plungers, and at their front ends with vents *t* to provide an avenue of escape for any pressure fluid which may leak into the plunger 25 chambers forwardly of the plungers.

Preferably the plungers *p* and *q* are controlled by the piston *C* and to this end a kicker passage *u* is formed in the cylinder *B* to lead from the piston chamber *H* rearwardly 30 of the exhaust port to a point intermediate the end of the plunger chamber *j* where it may register with a transverse passage *v* in the plunger *p*. The passage *v* in turn communicates with a passage *w* in the plunger 35 having its outlet opening in the rearward end of the plunger *p*.

Similarly a kicker passage *x* is formed in the cylinder *B* to lead from the piston chamber *H* at a point forwardly of the exhaust 40 ports to the plunger chamber *k*. The plunger *q* in the plunger chamber *k*, like the plunger *p*, is also provided with a transverse passage or passages *v* which may register with the kicker passage *x* and open into the passage 45 *w* in the plunger for conveying pressure fluid to the rearward end of the plunger chamber *k*.

In the construction shown, a cover is provided for the rearward ends of the plunger 50 chambers *j* and *k* in the form of a plate *y* which also acts as a seat for the rotation ratchet *R* and the head *O* of the rifle bar.

The operation of the device is as follows: 55 With the throttle valve *U* in the position illustrated, pressure fluid may flow through the passage *Y* into the reservoir *Z* from whence it will flow through the supply passage *d* to the valve chamber *c*. With the valve *e* in the position illustrated, pressure fluid will flow 60 over the raised or right hand end of the valve, thence through the inlet passage *g* into the rearward end of the piston chamber *H* to drive the piston *C* forwardly against the working implement.

65 After the piston *C* covers the exhaust ports,

the air in the front end of the piston chamber will be compressed and will flow through the inlet passage *h* to act against the other end of the valve *e*. As the piston *C* proceeds forwardly, the kicker passage *u* will be uncovered thereby and pressure fluid will then flow through the kicker passage *u* and the passages *v* and *w* in the plunger *p* into the rearward end of the valve chamber *j* to act against the rearward end of the plunger *p* for rocking the valve into a position to close the inlet passage *g*. When the plunger *p* has been thus depressed, the exhaust passage *s* of the plunger chamber *j* will be uncovered by the plunger and the pressure fluid used for actuating the plunger will proceed to leak from the plunger chamber to the atmosphere. 70

With the valve reversed in the manner described, pressure fluid will flow over the left hand end of the valve through the inlet passage *h* into the front end of the piston chamber *H* to return the piston to its initial position. As the piston proceeds rearwardly, it will cover the exhaust ports *D* and *E* and the air in the rearward end of the piston chamber *H* will be compressed to act against the seated or right hand end of the valve. Continuing rearwardly the piston *C* will uncover the kicker passage *x* and pressure fluid will then flow through the kicker passage *x* and through the passages *v* and *w* in the plunger *q* to depress said plunger and consequently tilt the valve to its initial position. Following this movement of the plunger *q*, pressure fluid will flow through the exhaust passage *s* of the valve chamber *k*, but this exhaust from the plunger chamber *k* will be slightly delayed due to the restricted area of the passage *s* so that ample pressure will remain in the plunger chamber *k* to maintain the seated end of the valve *e* firmly against the back cylinder washer *J*, which acts in this instance as a seat for the valve. This is advantageous at this period in the cycle of operations since it overcomes the force of the suction created upon the opposite or raised end of the valve by the pressure fluid flowing thereover into the piston chamber. 95

I claim:

1. In a fluid actuated rock drill, the combination of a cylinder and a piston, a free exhaust port in the cylinder controlled by the piston, a valve chest having a valve chamber, inlet passages leading from the valve chamber to the cylinder, an oscillatory plate valve in the valve chamber to control the inlet passages, plunger chambers in the valve chest, plungers in the plunger chambers extending into the valve chamber, and piston controlled kicker passages for conveying pressure fluid from the cylinder to the plunger chambers to press said plungers against the valve and hold said valve stationary during the admission of pressure fluid to the ends of the cylinder. 115

120

125

130

2. In a fluid actuated rock drill, the combination of a cylinder and a piston, a free exhaust port in the cylinder controlled by the piston, a valve chest having a valve chamber, inlet passages leading from the valve chamber to the cylinder, an oscillatory plate valve in the valve chamber to control the inlet passages, plunger chambers in the valve chest, plungers in the plunger chambers extending into the valve chamber, and piston controlled kicker passages for conveying pressure fluid from the cylinder to the plunger chambers to act against one end of the plungers for pressing said plungers against the seated end of the valve for holding the valve against fluttering during the admission of pressure fluid into the cylinder.

3. In a fluid actuated rock drill, the combination of a cylinder and a piston, a free exhaust port in the cylinder controlled by the piston, a valve chest having a valve chamber, inlet passages leading from the valve chamber to the cylinder, an oscillatory plate valve in the valve chamber to control the inlet passages, plunger chambers in the valve chest disposed perpendicularly with respect to the valve chamber, plungers in the plunger chambers having stems bearing against the valve, and kicker passages for conveying pressure fluid from the cylinder to the plunger chambers to act against the plungers for throwing the valve and for holding the valve against the effects of the suction created by the pressure fluid flowing over the raised portion of the valve.

4. In a fluid actuated rock drill, the combination of a cylinder and a piston, a free exhaust port in the cylinder controlled by the piston, a valve chest having a valve chamber, inlet passages leading from the valve chamber to the cylinder, an oscillatory plate valve in the valve chamber to control the inlet passages, plunger chambers in the valve chest disposed perpendicularly with respect to the valve chamber, plungers in the plunger chambers having stems bearing against the valve, and kicker passages for conveying pressure fluid from the cylinder to the plunger chambers, and passages in the plungers registering with the kicker passages for conveying pressure fluid to the rearward end of the plunger chambers to press the plungers against the valve for throwing the valve and for holding said valve against the effects of the suction created by the pressure fluid flowing over the raised portion of the valve.

In testimony whereof I have signed this specification.

THOMAS L. MURPHY.
